United States Patent Office

Des. 220,741
Patented May 18, 1971

220,741

BRASSIERE

Joseph P. Marcario, Saddle Brook, and Jack J. LoCascio,
Bayonne, N.J., assignors to Sarong, Inc., New York,
N.Y.

Filed Nov. 3, 1969, Ser. No. 19,877

Term of patent 14 years

Int. Cl. D2—02

U.S. Cl. D2—24

FIG. 1

Des. 220,741

PAGE 2

FIG. 2

Des. 220,741

FIG. 4

FIG. 1 is a front elevational view of a brassiere showing our new design;

FIG. 2 is a side perspective view thereof in wearing position;

FIG. 3 is a second embodiment of the design of FIG. 1 wherein the waist band portion is plain; and

FIG. 4 is a side perspective view thereof in wearing position.

We claim:

The ornamental design for a brassiere, as shown and described.
